(57) **CLAIM**

The ornamental design for a carabiner body, as shown and described.

DESCRIPTION

FIG. 1 is a front elevation with the wire-gate closed;

FIG. 2 is a rear elevation with the wire-gate open;

FIG. 3 is a top plan view;

FIG. 4 is a right side elevation view;

FIG. 5 is a left side elevation view; and,

FIG. 6 is a bottom plan view.

The broken lines showing a wire gate are for the purposes of illustrating environment and form no part of the claimed design.
